UNITED STATES PATENT OFFICE.

CHARLES H. HOYT, OF BEVERLY, MASSACHUSETTS, ASSIGNEE TO UNITED SHOE MACHINERY CORPORATION, OF PATERSON, NEW JERSEY, A CORPORATION OF NEW JERSEY.

WORK-SUPPORTING MEANS FOR SHOE-MACHINES.

1,399,771.

Specification of Letters Patent. Patented Dec. 13, 1921.

Application filed October 31, 1919. Serial No. 334,777.

To all whom it may concern:

Be it known that I, CHARLES H. HOYT, a citizen of the United States, residing at Beverly, in the county of Essex and State 5 of Massachusetts, have invented certain Improvements in Work-Supporting Means for Shoe-Machines, of which the following description, in connection with the accompanying drawings, is a specification, like reference characters on the drawing indicating 10 like parts in the several figures.

This invention relates to machines for use in the manufacture of boots and shoes, and has more particular reference to work supporting means for such machines. The invention is herein illustrated in its application to a machine for pulling uppers over lasts, and more particularly as applied to a type of construction of shoe support illustrated in a prior application of R. F. McFeely, Serial No. 211,849 filed on Jan. 14, 1918. It is to be understood, however, that in many of its aspects the invention is not restricted in utility to pulling-over machines nor limited to the particular type of shoe support illustrated in said application.

A feature of the invention consists in novel means for imparting movement to a shoe support to position it in the correct relation to a shoe. In the type of construction illustrated the shoe support is mounted for initial movement from an idle position to a position opposite to that part of the shoe which it is to engage and for movement 35 thence into operative relation to the shoe. The purpose of such an arrangement, as applied for example to a pulling-over machine, is to permit the shoe support to be positioned initially in such a location as not 40 to interfere with the operator's view of the work. In its application to a construction of this general type the invention provides novel means for imparting to the support its initial positioning movement relatively to the shoe, such movement in the construction shown being effected by spring operated mechanism under control of the starting means provided for initiating the cycle of operations of the machine.

50 In pulling-over machines of the illustrative type the cycle of operations is effected in successive automatically terminable stages each of which is initiated by a movement of the starting means, and it is required that

during the first stage of the cycle and the 55 succeeding period of rest the support for the top of the forepart of the shoe be maintained in its idle position. Accordingly a further feature of the invention, as applied to pulling-over and other machines, consists in 60 novel means of control for rendering the starting means in its first operative movement ineffective to cause the shoe support to be moved from its idle position and for rendering it subsequently effective to cause such 65 movement of the support.

A further feature of the invention consists in a novel construction of shoe support designed to engage the shoe with adequate supporting pressure while insuring against the 70 application of undue pressure such as might damage the work or involve the danger of breaking parts of the structure.

The above and other features of the invention, including certain details of construction and combinations of parts, will now be described with reference to the accompanying drawings and pointed out in the claims.

In the drawings:

Figure 1 is a view in side elevation of a 80 portion of a pulling-over machine including mechanism in which the invention is embodied, with parts broken away to reveal more fully the interior construction.

Fig. 2 is a view in front elevation of the 85 shoe support and portions of its operating mechanism, showing the support in its idle position.

Fig. 3 is a detail perspective view on an enlarged scale of a portion of the mechanism for controlling the movement of the support.

Fig. 4 is a fragmentary view partly in front elevation and partly in section on the line 4-4 of Fig. 1.

Fig. 5 is a view showing parts of the controlling mechanism of Fig. 1 in a different position, and

Fig. 6 is a view, partly in plan and partly in horizontal section on the line 6-6 of Fig. 1, illustrating certain details of the shoe support.

As shown and described in said prior application, and more fully as to certain details in prior patent No. 1,029,387 granted 105 on June 11, 1912, upon an application of R. F. McFeely, pulling-over machines of the type illustrated comprise in their general

organization grippers 2 and 4 for engaging the upper respectively at the toe end and at opposite sides of the forepart of a last positioned in operative relation to the grippers by means of a sole rest 6 and a heel rest 8, and means automatically operative upon the starting of the machine to impart an upper pulling movement to said grippers and then to bring the parts of the machine 10 to rest with the upper held under tension. Such machines also usually include in their organization toe and side overlaying and tacking devices 10 and 12 to wipe the margin of the upper inwardly over the bottom 15 of the last and secure it in overwiped position, these devices being operated by power driven mechanism in the final stage of the cycle of operations. While the particular number of stops which the machine makes 20 in its cycle is immaterial to the present invention, it will be assumed that the cycle of operations is effected in two stages, with a single period of rest between the beginning and the end of the cycle to permit any necessary adjustment of the upper while it is held 25 under tension by the grippers. The cycle of movements is controlled by well-known mechanism, as explained in said prior application and in greater detail in Patent 30 No. 791,986 granted on June 6, 1905 upon an application of R. F. McFeely. It is sufficient for the purposes of the present description to state that the controlling means includes a treadle 14 connected by means 35 of a rod 16 to a lever 18 for imparting movement at the required time to a clutch actuating rod 20 whereby the machine is started at each stage of the cycle.

After the upper has been pulled, and prior 40 to the operative movement of the overlaying and tacking devices, a shoe support is moved into engagement with the top of the forepart of the shoe to assist in positioning and holding the shoe for the overlaying and 45 tacking operations. As in the construction shown and described in said prior application, the shoe support herein shown comprises a pair of pads 22 arranged to engage the upper at opposite sides of the longitudinal 50 median line of the shoe, these pads being mounted on holders 24 which by the pressure of the pads against the shoe are caused to swing outwardly about a pivot 26 on a supporting stem 28 against the resistance 55 of a spring 30. The stem 28 is mounted, in a manner hereinafter explained, in a bracket 32 which has a depending part movable vertically in a guideway on the upper end of a supporting arm 34 to adjust 60 the pads 22 lengthwise of the shoe. A pin 36 in engagement with teeth 38 on the bracket 32 serves to retain the bracket in adjusted position. The arm 34 is mounted to swing laterally of the shoe on a pivot 40 65 which is journaled in the upper end of a

supporting arm 42, this arm being mounted to swing about a pivot stud 44 at right angles to the pivot 40. The arm 42 is connected by means of a link 46 to a slide 48 which is operated by a cam, not herein shown, to swing the arm about its bearing 44. As shown in Fig. 2, the arm 34 in its idle position is inclined laterally of the shoe in such manner as to position the shoe engaging means substantially at one side 70 of the shoe to permit the work to be readily presented to or removed from the machine, and also to permit the operator to have an unobstructed view of the top of the forepart of the shoe in order to determine whether the upper has been properly pulled with its lines in the correct relation to the last. From its idle position the arm 34 is swung about the axis of the pivot 40 to present the shoe engaging means substantially opposite 80 to the top of the forepart of the shoe with the pads 22 in symmetrical relation to the sides of the shoe. Upon the subsequent starting of the machine the arm 42 receives its operative movement from the cam slide 85 48 to swing the arm 34 about the axis of the pivot 44 and carry the shoe engaging portion of the support into operative relation to the shoe.

In the construction shown the lateral 90 swinging movement of the arm 34, prior to its movement about the bearing 44, is effected by spring operated mechanism controlled by the treadle operated lever 18. This mechanism comprises a lever arm 50 100 mounted on the same pivot 52 as the lever 18 and carrying at its upper end a wedge block 54 which upon rearward swinging movement of the lever is arranged to engage the rounded end of a plunger 56 mounted 105 in a socket in the lower end portion of the arm 34 and backed up by a spring 58. It will be understood that this spring is of sufficient strength to render the wedge block effective to swing the arm 34 laterally to its 110 required operative position, as determined adjustably by the engagement of a nut 60 on the lower end of the arm 34 with the frame 61 of the machine, while permitting the plunger 56 to yield in response to the pressure of the wedge block when the movement of the arm is stopped. Operative movement of the lever 50 is effected by means of springs 62 and 64 which are mounted respectively on rods 66 and 68 fast on blocks 70 115 and 72 which are pivotally connected to the lever 50. The rod 66 is arranged to slide lengthwise through an opening in the frame of the machine and the rear end of the spring 62 abuts against the frame. The rod 120 68 is arranged to slide similarly through an opening in a laterally offset lug 74 on the lower end portion of the arm 42 and carries a nut 76 for engagement with the lug 74 on the opposite side from the spring 64.

By reference to Fig. 1 it will be evident that the lug 74 by its engagement with the nut 76 is utilized to swing the arm 50 reversely to its idle position. In order to hold the arm in this position until such time as it is required to operate, the machine is provided with a latch 78 which is arranged to hook over a lug 80 fast on the side of the arm. This latch is secured to a pin 82 which is mounted to turn in a bearing in a bracket 84 on the frame of the machine and is provided at its opposite end with an arm 86 on which is pivoted a block 88 in position to be engaged by a projection 90 on the lever 18. A stop 92 on the arm 86 is arranged to determine the normal position of the block 88 in which the block is held yieldingly by means of a spring 94. It will be evident that when the treadle 14 is first operated to initiate the first period of the cycle of operations of the machine the projection 90 on the end of the lever 18 by its engagement with the block 88 serves to swing the arm 86 upwardly and thus to withdraw the latch 78 from engagement with the lug 80. At this time, however, the arm 50 is positively held against movement in response to the pressure of the springs 62 and 64 by the action of the lug 74 on the nut 76, the arm 42 being held in the position illustrated in Fig. 1 by means of its cam operated mechanism. In the movement of the lever 18 the projection 90 finally slips past the block 88, whereupon the latch 78 is returned into operative relation to the lug 80 by means of a spring 87. When the lever 18 is returned to its initial position upon the release of the treadle, the block 88 yields to permit the projection 90 to pass and resume its initial relation to the block. In the first period of the cycle, wherein the pulling of the upper is effected as hereinbefore explained, the slide 48 receives a short operative movement such as to swing the arm 42 about its bearing 44 a sufficient distance to space the lug 74 from the nut 76, as indicated in Fig. 5, such movement, however, being insufficient to swing the shoe engaging portion of the support 50 far enough rearwardly to interfere with its subsequent lateral movement. Upon the next depression of the treadle 14 to initiate the second and final period of the cycle of operations, the latch 78 is elevated as before, and upon its release of the lug 80 both springs 62 and 64 are rendered effective to impart a swinging movement to the arm 50 of sufficient extent to cause the arm 34 to be swung laterally to its required position by the action of the wedge block 54. Immediately following such lateral swinging movement of the arm 34, the slide 48 receives a further movement from its cam to swing the arms 42 and 34 about the bearing 44 to their final operative position and to hold them in such position during the operation of the overlaying and tacking devices. In the return of the parts to starting position the lug 74 on the arm 42 operates in engagement with the nut 76 to swing the arm 50 reversely until it is caught by the latch 78 which yields against the pressure of the spring 87 in response to the wedging action of the lug 80. The arm 34 is thus released by the wedge block 54 and is permitted to swing by gravity to its idle position illustrated in Fig. 2. A spring pressed plug 96 on the lower end of the arm 34 on the opposite side from the nut 60 serves by engagement with the frame 61 to limit the swinging movement of the arm and to avoid any objectionable shock of impact.

By reference to Fig. 6 it will be seen that the stem 28 which carries the shoe engaging pads is mounted slidably in a socket 85 in the bracket 32 and is provided within its hollow interior with a pair of springs 98 and 100 which are backed up by an adjustable thread plug 102. The spring 98 is considerably weaker than the spring 100 and is arranged to yield in response to resistance of the shoe to permit relative movement between the stem 28 and the bracket 32 as the arm 34 is swung into operative position, during which time the pads 22 are forced apart to stretch the upper and to seat them firmly against the shoe. The stronger spring 100 is arranged to come into play substantially at the time when the arm 34 arrives at its limit of operative movement to oppose a resistance to relative movement between the bracket and the stem which is substantially unyielding against the normal pressure applied to the shoe in the overlaying and fastening operations. The construction thus serves to provide an effective support for the shoe while avoiding danger of breakage of the parts or damage to the shoe, since it will be understood that while the spring 100 is substantially unyielding against the pressure applied to the shoe in the overlaying and fastening operations it may yield in the movement of the support to operative position sufficiently to accommodate the mechanism within the limits of safety to varying conditions encountered in operating upon shoes of different sizes and styles.

Having described the invention, what I claim as new and desire to secure by Letters Patent of the United States is:

1. In a machine of the class described, the combination with means for operating on a shoe, of a shoe support mounted for movement from an idle position into operative relation to the shoe, and separately operated power mechanisms arranged to act in succession to initiate and to complete respectively the movement of the support into operative relation to the shoe.
2. In a machine of the class described, the

- combination with means for operating on a shoe, of a shoe support mounted for movement from an idle position into operative relation to the shoe, power mechanism automatically operative after the starting of the machine to seat said support in its final operative relation to the shoe, and additional mechanism operative as an incident to the starting of the machine to impart an initial positioning movement to said support.
3. In a machine of the class described, the combination with means for operating on a shoe, of a shoe support mounted for movement from an idle position into operative relation to the shoe, means for starting the machine, power mechanism automatically operative upon the starting of the machine to seat said support in its final operative relation to the shoe, and additional spring operated mechanism arranged to be actuated by said starting means and to impart an initial positioning movement to said support.
4. In a machine of the class described, the combination with means for operating on a shoe, of a shoe support mounted for positioning movement relatively to the shoe and for movement in a different direction into operative relation to the shoe, power operated mechanism for imparting said last named movement to the shoe support, and additional power operated mechanism for imparting to the shoe support said positioning movement.
5. In a machine of the class described, the combination with means for operating on a shoe, of a shoe support mounted for positioning movement relatively to the shoe and for movement in a different direction into operative relation to the shoe, power operated mechanisms arranged to act, each while the other is idle, to impart respectively said different movements to the shoe support, and a single means of control for both said mechanisms.
6. In a machine of the class described, the combination with means for operating on a shoe, of a shoe support mounted for positioning movement relatively to the shoe and for movement in a different direction into operative relation to the shoe, power mechanism arranged to operate upon the starting of the machine to impart said last named movement to the shoe support, and additional power mechanism for imparting to the support said positioning movement prior to the operation of said first mechanism.
7. In a machine of the class described, the combination with means for operating on a shoe, of a shoe support mounted for positioning movement relatively to the shoe and for movement in a different direction into operative relation to the shoe, power mechanism automatically operative after the starting of the machine to impart said last named movement to the shoe support, and additional mechanism operative as an incident to the starting of the machine to impart to the support said positioning movement.
8. In a machine of the class described, the combination with means for operating on a shoe, of a shoe support mounted for positioning movement relatively to the shoe and for movement in a different direction into operative relation to the shoe, means for starting the machine, power mechanism arranged to operate upon the starting of the machine to impart said last named movement to the shoe support, and additional mechanism controlled by said starting means for imparting to the support said positioning movement.
9. In a machine of the class described, the combination with means for operating on a shoe, of a shoe support mounted for positioning movement relatively to the shoe and for movement in a different direction into operative relation to the shoe, power operated means for imparting said last named movement to the shoe support, and additional spring operated means for imparting to the support said positioning movement.
10. In a machine of the class described, the combination with means for operating on a shoe, of a shoe support mounted for positioning movement relatively to the shoe and for additional movement into operative relation to the shoe, means for starting the machine, power means arranged to operate upon the starting of the machine to impart said last named movement to the shoe support, and spring operated mechanism arranged to be controlled by said starting means and to impart to the support said positioning movement.
11. In a machine of the class described, the combination with means for operating on a shoe, of a shoe support mounted for positioning movement relatively to the shoe and for additional movement into operative relation to the shoe, power operated means for imparting said last named movement to the shoe support, spring operated mechanism for imparting to the support said positioning movement, means for locking said mechanism in inoperative position, and means for operating said locking means to release said mechanism.
12. In a machine of the class described, the combination with means for operating on a shoe, of a shoe support mounted for positioning movement relatively to the shoe and for additional movement into operative relation to the shoe, means for starting the machine, power means arranged to operate

- upon the starting of the machine to impart said last named movement to the shoe support, spring operated mechanism for imparting to the support said positioning movement, means comprising a latch for holding said mechanism in inoperative position, and means arranged to be operated by the starting means to trip said latch.
13. In a machine of the class described, 10 the combination with means for operating on a shoe, of a shoe support mounted for positioning movement relatively to the shoe and for additional movement into operative relation to the shoe, power operated means for 15 imparting said last named movement to the shoe support, spring operated mechanism for imparting to the support said positioning movement, locking means for holding said mechanism in inoperative position, means 20 for operating said locking means to release the mechanism, and additional power operated means for returning said mechanism into position to be held by the locking means.
14. In a machine of the class described, 25 the combination with means for operating on a shoe, of a shoe support mounted for positioning movement relatively to the shoe, spring operated mechanism for imparting said movement to the shoe support, locking 30 means for holding said mechanism normally in inoperative position, and means for operating said locking means to release the mechanism.
15. In a machine of the class described, 35 the combination with means for operating on a shoe, of a shoe support mounted for positioning movement relatively to the shoe, spring operated mechanism for imparting said movement to the shoe support, locking 40 means arranged to be operated to release said mechanism, and additional means for returning the mechanism into position to be held by said locking means.
16. In a machine of the class described, 45 the combination with means for operating on a shoe, of a shoe support mounted for movement from an idle position into operative relation to the shoe, spring operated mechanism for imparting a positioning 50 movement to said support, a locking device arranged to be operated to release said mechanism, additional means for moving said support away from the shoe, and means operated by the last named movement of the 55 support to return said mechanism into position to be held by said locking device.
17. In a machine of the class described, the combination with means for operating on a shoe, of a shoe support mounted for positioning movement relatively to the shoe, means for starting the machine, spring operated mechanism for imparting said movement to the shoe support, locking means for holding said mechanism normally in inoperative position, and means for operating said
- locking means by the starting means to release said mechanism.
18. In a machine of the class described, the combination with means for operating on a shoe, of a shoe support mounted for 70 movement in a direction transverse to the height of the shoe to a position substantially opposite to the top of the forepart of the shoe and for movement thence heightwise of the shoe into supporting relation to said 75 forepart, and separately operated power mechanisms for imparting to the support respectively said different movements.
19. In a machine of the class described, the combination with means for operating 80 on a shoe, of a shoe support mounted for positioning movement laterally of the shoe and for movement in a different direction into engagement with the top of the forepart of the shoe, power mechanism arranged 85 to operate upon the starting of the machine to impart said last named movement to the shoe support, and spring operated mechanism for imparting to said support its positioning movement.
20. In a machine of the class described, the combination with power means for operating on a shoe and means for starting the machine in operation, of a shoe support mounted for positioning movement in a direction transverse to the height of the shoe to a location substantially opposite to the top 95 of the forepart of the shoe and for movement thence heightwise of the shoe into supporting relation to said forepart, power 100 driven mechanism automatically operative after the starting of the machine to impart said last named movement to the shoe support, and additional mechanism operative as an incident to the starting of the machine 105 to impart to the support said positioning movement.
21. In a machine of the class described, the combination with means for operating on a shoe, of a shoe support mounted for 110 preliminary movement to a position substantially opposite to the top of the forepart of the shoe and for movement thence into supporting relation to the fore part of the shoe, means for starting the machine, 115 power means arranged to operate upon the starting of the machine to impart said last named movement to the shoe support, and spring operated mechanism arranged to be released by said starting means and to impart said preliminary movement to the support.
22. In a machine of the class described, the combination with means for operating on a shoe, of a shoe support mounted for 125 swinging movement laterally of the shoe to a position substantially opposite to the top of the foremost of the shoe and for movement thence into engagement with the shoe, and wedge mechanism for imparting said 130

lateral swinging movement to the shoe support before it is carried into engagement with the shoe.

23. In a machine of the class described, the combination with means for operating on a shoe, of a shoe support comprising means for engaging the shoe on the top of the forepart at opposite sides of the longitudinal median line of the shoe, an arm on which said shoe engaging means is supported, said arm being mounted for movement laterally of the shoe and for movement in a different direction to carry said shoe engaging means into operative relation to the shoe, and power means automatically operative to impart said different movements to the arm.

24. In a machine of the class described, the combination with means for operating on a shoe, of a shoe support comprising members arranged to engage the shoe on the top of the forepart at opposite sides of the longitudinal median line of the shoe, an arm on which said members are mounted, said arm being mounted for swinging movement laterally of the shoe and for movement in a different direction to carry said members into engagement with the shoe, and means automatically operative to impart said lateral swinging movement to the arm before said members are carried into engagement with the shoe.

25. In a machine of the class described, the combination with means for operating on a shoe, of a support for engaging the shoe at the top of the forepart, said support being mounted for swinging movement laterally of the shoe prior to its engagement with the shoe, and spring operated wedge mechanism for imparting said swinging movement to the support.

26. In a machine of the class described, the combination with means for operating on a shoe, of a support for engaging the shoe at the top of the forepart, said support being mounted for swinging movement laterally of the shoe prior to its engagement with the shoe, means for starting the machine, and spring operated mechanism controlled by said starting means for imparting said swinging movement to the support.

27. In a machine of the class described, the combination with means for operating on a shoe, of a support for engaging the shoe at the top of the forepart, said support being mounted for swinging movement laterally of the shoe prior to its engagement with the shoe, spring operated mechanism for imparting said swinging movement to the support, a locking device for holding said mechanism normally in inoperative position, and means automatically operative as an incident to the starting of the machine to cause said locking device to release said mechanism.

28. In a machine of the class described, the combination with power operated means for performing different operations on a shoe in different automatically terminable stages of the cycle of the machine, of starting means for initiating each stage of the cycle, a shoe support mounted for movement from an idle position into operative relation to the shoe, mechanism arranged to be actuated by said starting means and to impart a positioning movement to said support, and means for rendering the starting means in its first starting movement ineffective to cause the support to be moved by said mechanism and for rendering it subsequently effective to cause such movement of the support.

29. In a machine of the class described, the combination with power operated means for performing different operations on a shoe in different automatically terminable stages of the cycle of the machine, of starting means for initiating each stage of the cycle, a shoe support arranged to be positioned initially in inoperative relation to the shoe, spring operated mechanism for imparting to said support a positioning movement relatively to the shoe, a device for initiating the operation of said mechanism, means for rendering the starting means effective in each of its starting movements to operate said device, and additional controlling means for preventing the operation of said mechanism in the first operation of the starting means.

30. In a machine of the class described, the combination with power operated means for performing different operations on a shoe in different automatically terminable stages of the cycle of the machine, of starting means for initiating each stage of the cycle, a shoe support arranged to be positioned initially in inoperative relation to the shoe, spring operated mechanism for imparting to said support a positioning movement relatively to the shoe, a locking device for holding said mechanism normally inoperative, means for operating the locking device to release said mechanism at each operation of the starting means, and additional controlling means arranged to hold said mechanism in its inoperative position when the mechanism is first released by the starting means and to move into such position as to permit the operation of said mechanism when it is subsequently released by the starting means.

31. In a machine of the class described, the combination with power operated means for performing different operations on a shoe in different automatically terminable stages of the cycle of the machine, of starting means for initiating each stage of the cycle, a shoe support arranged to be positioned initially in inoperative relation to the shoe, spring operated mechanism for im-

- parting to said support a positioning movement relatively to the shoe, a locking device for holding said mechanism normally inoperative, means for operating the locking device to release said mechanism at each operation of the starting means, and additional means arranged to coöperate with the starting means to control said mechanism and to return the mechanism finally into position to be held by said device. 45
32. In a machine of the class described, the combination with means for operating with pressure against the bottom of a shoe, of a shoe support arranged to engage the shoe on the top of the forepart and comprising parts relatively movable in response to pressure between the support and the shoe, a spring arranged to yield in such relative movement of the parts, a second spring arranged to come into play in such relative movement to oppose an increased resistance to the pressure on the shoe, and power operated means for controlling said shoe support. 50
33. In a machine of the class described, the combination with means for operating on a shoe, of a shoe support comprising parts relatively movable in response to pressure between the support and the shoe, a spring arranged to yield in such relative movement of the parts, and a second stronger spring arranged to come into play to prevent substantially such relative movement of the parts in response to the normal pressure of said operating means on the shoe while affording provision for yield to accommodate the support to different sizes and styles of shoes. 55
34. In a machine of the class described, the combination with means for operating on a shoe, of a shoe support mounted for movement into engagement with the shoe and comprising parts relatively movable in response to resistance of the shoe, a spring 60
- arranged to yield in such relative movement of the parts, and a second spring arranged to come into play to oppose substantially unyielding resistance to the normal pressure of said operating means on the shoe when the shoe support is in its final operative position. 65
35. In a machine of the class described, the combination with means for operating on a shoe, of a shoe support mounted for movement into engagement with the shoe and comprising parts relatively movable in response to resistance of the shoe, a spring arranged to yield in such relative movement of the parts, and a second stronger spring arranged to oppose substantially unyielding resistance to the normal pressure of said operating means on the shoe when the support is in its final operative position and to yield in response to abnormal pressure between the shoe and the support to avoid danger of breakage of the machine or of damage to the shoe. 70
36. In a machine of the class described, the combination with means for operating on a shoe, of a shoe support comprising members arranged to engage the shoe on the top of the forepart at opposite sides of the longitudinal median line of the shoe and mounted for relative separating movement in response to pressure of the shoe, a stem 75 on which said members are supported, a holder in which said stem is slidably mounted to yield in response to resistance of the shoe, a spring compressible in response to the yield of said stem, and a second stronger spring arranged to come into play to oppose substantially unyielding resistance to movement of said stem in its holder in response to the normal pressure of the operating means upon the shoe. 80
- In testimony whereof I have signed my name to this specification. 85

CHARLES H. HOYT.
